INDICATING APPARATUS

Arthur E. Dodd, Edgewood, Pa., assignor to The Union Switch & Signal Company, Swissvale, Pa., a corporation of Pennsylvania

Application November 20, 1943, Serial No. 511,069

3 Claims. (Cl. 246—122)

My invention relates to indicating apparatus, and particularly to apparatus in which an indicating device is operated momentarily in response to a change in a given condition.

In apparatus in which an indicating device is operated for a brief period of time by means of the charging current for a condenser, it is desirable, for best results, that in preparation for each such operation the condenser should be discharged as completely as possible.

One feature of my invention is the provision of means comprising a circuit of very low resistance closed for a brief period of time for discharging a condenser in indicating apparatus in which the charging current for the condenser is employed for operating an indicating device.

I shall describe two forms of apparatus embodying my invention, and shall then point out the novel features thereof in claims.

In the accompanying drawing, Fig. 1 is a diagrammatic view showing one form of apparatus embodying my invention, in which an indicating device is operated momentarily by the current which charges a condenser, and in which the condenser becomes discharged by a very low resistance circuit; Fig. 1a is a diagrammatic view showing the resistances of the various parts in the arrangement shown in Fig. 1; and Fig. 2 is a diagrammatic view showing a modification of the arrangement of Fig. 1 including an asymmetric unit in series with the indicating device.

Similar reference characters refer to similar parts in each of the views.

Referring first to Fig. 1, a stretch of railway track is shown divided by insulated joints 1 into sections 2T, 3T and 4T. Each of the sections 2T, 3T and 4T is provided with a track circuit including a battery 5 connected across the rails adjacent one end of the section, and including a track relay designated by reference character 2R, 3R or 4R, respectively, connected across the rails adjacent the opposite end of the section.

As shown in the drawing, section 4T is occupied by a car or train 4N, and hence relay 4R is deenergized; section 3T is unoccupied, and hence relay 3R is energized; and a car or train 2N is just entering section 2T, and relay 2R is therefore just changing from the energized to the deenergized position.

Each of the track relays is equipped with a movable contact element comprising a flexible upper finger 6a and a flexible lower finger 6b. The energized position of the contact element of each of these relays is as shown for relay 3R. Since contact finger 6a of relay 3R bears against

its front contact point it is bent by the contact pressure, whereas contact finger 6b is out of engagement with its back contact point and is therefore not bent. The deenergized position of the contact element of each of the relays is as shown for relay 4R. Contact finger 6a of relay 4R is out of engagement with its front point and is therefore straight because the front contact pressure is relieved, whereas contact finger 6b of relay 4R is in engagement with its back contact point and is therefore slightly bent. When the condition of any one of these relays is changed from deenergized to energized, or from energized to deenergized as shown for relay 2R, its contact finger 6a is in engagement with its front contact point for a brief period while its contact finger 6b is in engagement with its back contact point. During this brief period, a branch path is closed from the front contact point, through finger 6a, finger 6b, and the back point, for discharging a high-capacity electrolytic condenser C.

An indicating device, shown as a bell B, is connected in a circuit in series with condenser C and a suitable source of current, such for example as a battery Q.

In Fig. 1a, the resistances of the various parts of the apparatus shown in Fig. 1 are represented by resistors designated by the reference character *r* followed by the reference character for the corresponding part. The internal resistance of battery Q is therefore shown as a resistor *rQ*; the combined resistances of conductors 7, 8a, and 9a of Fig. 1 are shown as a resistor *r1—8a—9a*; the resistance of bell B is shown as a resistor *rB*; the combined resistances of conductors 8 and 9 and the internal resistance of condenser C are shown as a resistor *rC—8—9*; and the combined resistances of conductors 8b and 9b and a contact element 6a—6b are shown as a resistor *r8—8b—9b*.

Condenser C is normally charged to the potential of the current source Q, and therefore only the leakage current of the condenser 45 normally flows through the winding of bell B in a circuit passing from battery Q, through conductor 7, winding of bell B, conductors 8a and 8, condenser C, and conductors 9 and 9a back to battery Q.

50 Whenever one of the contact elements 6a—6b bridges, for a brief period its front and back contact points, when a corresponding relay becomes energized or deenergized, condenser C becomes discharged over a circuit path, such for example as the one shown closed by contact element

6a—6b of relay 2R, passing from condenser C, through conductors 8 and 8b, contact element 6a—6b of relay 2R, and conductors 9b and 9 back to condenser C. The discharge current which flows over one of these paths is limited by resistances $rC-8-9$ and $r6-8b-9b$ shown in Fig. 1a. By having these resistances very low, condenser C will be almost completely discharged in a very short period of time.

As soon as contact 6a—6b opens, at its front point, the discharge path traced for condenser C, the circuit previously traced through bell B will start charging the condenser. The charging current now flowing will operate bell B. If this bell is of the single stroke type, the charging current, upon starting to flow, will operate bell B to pick up a plunger which strikes a gong. When condenser C has become charged, the plunger will drop back to its deenergized position. The resistance rB of the bell B is fairly large, and hence resistances rQ and $r1-8a-9a$ may also have considerable value without greatly reducing the charging current for condenser C.

Referring now to Fig. 2, a modification of the arrangement of Fig. 1 is here shown, in which a full wave rectifier F, comprising asymmetric units $f1, f2, f3$ and $f4$, connected across terminals X and Y of a suitable alternating current supply, is used instead of battery Q, shown in Fig. 1, as the source of current. A variable load L is also energized by current from rectifier F. If load L had only inductance or resistance, the average voltage supplied by rectifier F across load L, if condenser C were not present, would be considerably lower than the peak voltage supplied by rectifier F. The condenser C provides appreciable filtering of the rectifier output when load L becomes light or is removed entirely, and may cause the average voltage across the load L to rise to almost the peak voltage of the rectifier. In cases where such a variation in average voltage across load L is undesirable, a blocking rectifier G may be connected between load L and condenser C in order to prevent the condenser C from filtering the entire rectifier output. Without rectifier G, the reversal of current flow through bell B, due to the filtering action of condenser C, might also adversely affect the operation of bell B.

Although the internal resistance rQ of the battery Q shown in Fig. 1 may be very low, the corresponding internal resistance of a rectifier F,

shown in Fig. 2, may be considerable, but the operation of the apparatus in both instances will be entirely satisfactory.

Although I have herein shown and described only two forms of indicating apparatus embodying my invention, it is understood that various changes and modifications may be made therein within the scope of the appended claims without departing from the spirit and scope of my invention.

Having thus described my invention, what I claim is:

1. In indicating apparatus for a stretch of railway track including an indicating device and a source of current and also a condenser, the combination comprising, a circuit for charging said condenser by current from said source and for at the same time operating said indicating device, and a traffic responsive contact for discharging said condenser while said contact is closed momentarily when a train enters said stretch of track and again when the train leaves said stretch.

2. In indicating apparatus for a stretch of railway track including an indicating device and a source of current and also a condenser, the combination comprising, a circuit including said source of current and said indicating device and said condenser all in series for charging said condenser and operating said indicating device, during charging of said condenser, and traffic responsive means for momentarily discharging said condenser when a train enters said stretch of track and again when the train leaves said stretch.

3. In indicating apparatus for a stretch of railway track including an indicating device and a source of current and also a condenser and a traffic responsive contact which becomes closed momentarily when a train enters said stretch of track and also when a train leaves said stretch of track, the combination comprising, a circuit including said source of current and said indicating device and said condenser all in series for charging said condenser and operating said indicating device during charging of said condenser while said traffic responsive contact is open, and a branch path including said contact connected across said condenser for discharging said condenser while said contact is closed.

ARTHUR E. DODD.
